UNITED STATES PATENT OFFICE

130,812

DESIGN FOR A BOOK END

Edward H. Calvert, Los Angeles, Calif.

Application April 10, 1941, Serial No. 100,292

Term of patent 7 years

To all whom it may concern:

Be it known that I, Edward H. Calvert, a citizen of the United States, residing at Los Angeles, in the county of Los Angeles and State of California, have invented a new, original, and ornamental Design for a Book End, of which the following is a specification, reference being had to the accompanying drawing, forming part thereof.

I claim:

The ornamental design for a book end, as shown.

EDWARD H. CALVERT.
